UNITED STATES PATENT OFFICE

168,382

HAT AND CLOTHES RACK

Laurence W. Sloan, Sr., Montebello, and Clifford J. Bonk, Los Angeles, Calif.

Application July 7, 1952, Serial No. 20,492

Term of patent 14 years

(Cl. D33—8)

To all whom it may concern:

Be it known that we, Laurence W. Sloan, Sr., and Clifford J. Bonk, citizens of the United States, residing, respectively, at Montebello, county of Los Angeles, State of California, and Los Angeles, county of Los Angeles, State of California, have invented a new, original, and ornamental Design for a Hat and Clothes Rack, of which the following is a specification, reference being had to the accompanying drawing, forming a part thereof, and in which:

Fig. 1 is an elevational view of the hat and clothes rack, showing our new design.

Fig. 2 is an elevational view taken at right angles to Fig. 1.

We claim:

The ornamental design for a hat and clothes rack, as shown.

LAURENCE W. SLOAN, SR.
CLIFFORD J. BONK.
